TEMPERATURE RESPONSIVE VALVE

Homer F. Malone and Lloyd E. Quint, Jackson, Mich., assignors, by mesne assignments, to Mechanical Products, Inc., Jackson, Mich., a corporation of Delaware

Filed July 3, 1962, Ser. No. 207,263

1 Claim. (Cl. 236—48)

This invention relates generally to valves and more particularly to an improved temperature responsive valve.

Increasing awareness of the air pollution problem and the effect of internal combustion engine exhaust or air pollution has spurred the development of catalytic mufflers that oxidize many of the hydrocarbons contained in such exhaust gases. Such catalytic type mufflers effect oxidization of the excess hydrocarbons in the exhaust gases of an internal combustion engine by a relatively high temperature process.

Upon the occurrence of certain conditions, for example, misfiring of the engine, at which time raw gasoline is discharged into the catalytic bed, the temperature of the bed may rise to dangerously high levels. When such a high temperature condition obtains, it is desirable to bypass the exhaust gases around the catalytic bed in order to allow the catalytic bed to cool off.

One way to bypass the catalytic bed of such mufflers is by using a vacuum operated flow control valve which directs the flow of exhaust gases either through the catalytic bed of the muffler, or through a bypass. The vacuum operated flow control valve is, in turn, controlled by a temperature responsive valve that senses conditions within the catalytic bed of the muffler.

A temperature responsive valve suitable for controlling the flow control valve of a catalytic muffler must be of relatively rugged construction so as to be impervious to the environmental conditions within the catalytic bed in which it operates, as well as be responsive to the temperature extremes to which it is subjected. It must be positive in operation, yet maintain its calibration through all temperature ranges.

A temperature responsive valve in accordance with the instant invention is designed to effect positive control of a vacuum system in response to variations in temperature in a catalytic bed thereby to control a vacuum-operated bypass valve. The temperature responsive valve features a high temperature section that is essentially thermally isolated from a valve section thereof. Movement of a thermally responsive element in the high temperature section is transmitted to a novel valve arrangement in the valve section, thereby to control the vacuum operated valve, which may be at a remote location.

Accordingly, one object of the instant invention is an improved temperature responsive valve.

Another object is an improved snap-acting temperature responsive valve.

Another object of the instant invention is an improved temperature responsive valve that effects thermal isolation of a high temperature section from a valve section.

Other objects and advantages of the disclosed exemplary embodiment of the instant invention will be apparent in the following specification, claim and drawings wherein:

FIGURE 1 is a side elevational view of a temperature responsive valve in accordance with one embodiment of the instant invention;

FIGURE 2 is a cross sectional view taken substantially along the line 2—2 of FIGURE 1; and

FIGURE 3 is a fragmentary view similar to FIGURE 1 showing the snap-action blade and valve in the open condition.

As best seen in FIGURE 1 of the drawings, a snap-acting temperature responsive valve 200, in accordance

2

with an exemplary embodiment of the instant invention, comprises a thermally responsive section 202 and a valve section 204. The temperature responsive valve 200, is adapted to be secured to the outer wall of, for example, a catalytic type muffler, as by turning a threaded section 206 on a fitting 208 into a complementary aperture in the muffler (not shown).

The temperature responsive section 202 comprises a tubular member 210 having a positive coefficient of expansion that is secured to the fitting 208 as by welding. The tubular member 210 is closed by an end plug 212 that is secured thereto as by welding. The end plug 24 has a truncated conical seat 214 for the acceptance and positioning of an outer end portion 216 of a rod 218. The rod 218 is made from material, for example, quartz, that is essentially thermally nonresponsive.

An inner end portion 220 of a rod extension 221 bears directly against a nondevelopable surface 222 of a snap-acting blade 224. The snap-acting blade 224 is secured to a mounting bracket 225 as by a pair of rivets 226 and 227 (FIGURE 3). The mounting bracket 225 is of generally U-shaped construction, leg portions 230 and 232 thereof terminating in foot portions 234 and 236, respectively. The foot portions 234 and 236 of the mounting bracket 225 are secured to a base plate 238, as by a pair of rivets 240 and 242.

A blade control spring 250 is secured to the mounting bracket 225 by the rivets 226 and 227 and has an end portion 252 that continuously engages the center of the nondevelopable surface 222 on the blade 224 against the end portion 220 of the rod 221 at all times.

A calibrating screw 254 extends into a threaded bore 256 in the base plate 238, in outer end portion 258 thereof being accepted in a complementary slot 260 in the bracket 225.

A cover member 261 is secured to the base plate 238 as by crimping an edge portion 262 over the base plate 238 and to this fitting 208 as by welding.

A free end portion 270 of the snap blade 224 is engageable with a ball type valve 272 that is adapted to be seated on a truncated conical valve seat 274 in a valve fitting 276. The ball valve 272 is normally biased to the open condition by a helical compression spring 278 that extends between a seat 280 in the valve fitting 276 and the ball 272 itself. Movement of the ball valve 272 under the bias of the spring 278 is controlled by the position of the end portion 270 of the blade 224 which is, in turn, controlled by longitudinal expansion and contraction of the tube 210 due to a change in environmental temperature condition. Opening movement of the end portion 270 of the blade 224 is limited by an adjustment screw 286.

A flow path through the valve section 204 of the temperature responsive valve 200 is effected by a central passage 290 in the valve fitting 276, which communicates with the interior of the valve section 204 upon opening of the ball valve 272. An aperture 292 in the base plate 238 provides a flow path through the valve section 204.

From a study of the orientation of the above described structural elements, it should be apparent that relatively exact calibration of the valve section 204 can be accomplished by advancement or retraction of the calibrating screw 254 and adjustment screw 286 which controls opening and closing movement of the blade 224 and thus the valve 272.

It is to be noted that a valve control member is normally biased into engagement with an element that is movable in direct relation to changes in the thermal environment. Since the valve control member is thus biased into constant and intimate engagement with the thermally responsive element, there is a minimum of lost motion

between movement of the thermally responsive member and the valve control member.

In addition, the valve control member is mounted in a manner that facilitates calibration of the thermally responsive valve by adjustment of a readily accessible calibration screw. Advancement or retraction of the calibration screw results in varying the angular relationship between the fulcrum for the valve control member, the point of engagement with the thermally responsive element, and the point of engagement with the fluid flow control valve. In this manner, relatively exact control of the opening movement of the fluid flow control valve can be effected.

Further, the flow control valve of the instant invention is normally biased into engagement with the control member so that lost motion between the valve control member and the ball valve is minimized.

It is also to be noted that the valve and high temperature sections of the improved thermally responsive valve herein disclosed, are separated, thereby to minimize the inherently deleterious effect of the catalytic bed of a smog-reducing muffler on operation of the valve. However, the thermally responsive section is related to the valve section in such a manner that relatively minute movements of the thermally responsive member are positively transmitted to the valve section which react thereto.

It is to be understood that the specific construction of the improved temperature responsive valve herein disclosed and described is presented for the purpose of explanation and illustration and is not intended to indicate limits of the invention, the scope of which is defined by the following claim.

What is claimed is:

A temperature responsive valve comprising
a valve section

defining a fluid flow path including
a mounting base having

a conical valve seat thereon,

a ball type valve

aligned with the valve seat on said base and mov-

able into engagement and disengagement there-

with to close and open said flow path, respec-

tively, a valve spring constantly biasing said

valve away from said seat and

a snap-acting blade having one end portion adjustably supported by said base, said snap-acting blade hav-

ing

a nondevelopable surface and

a free end portion

for controlling movement of said valve, said valve spring constantly biasing said valve against the free end portion of said blade,

resilient means

on said base engageable with one side of the non-

developable surface of said blade for continu-

ously biasing said blade in one direction,

a thermally responsive section

substantially thermally isolated from said valve section comprising

a thermally responsive member having

one end portion

fixedly supported with respect to said base and

a free end portion,

a thermally nonresponsive member having

one end portion

engaging and movable with the free end por-

tion of said thermally responsive member,

and

another end portion

extending into said valve section into engage-

ment with the other side of the nondevel-

opable surface of said snap-acting blade,

said valve being movable into and out of

engagement with said valve seat upon move-

ment of the free end portion of said snap-

acting blade in response to movement of

said thermally responsive and nonrespon-

sive members.
